United States Patent Office

Des. 174,699
Patented May 10, 1955

174,699

MATCH BOOK COVER

James L. McLaughlin, Whiting, Ind.

Application December 22, 1954, Serial No. 33,653

Term of patent 7 years

(Cl. D48—29)

Fig. 1.

Fig. 2.

Fig. 3.

Fig. 4.

Fig. 5.

To all whom it may concern:

Be it known that I, James L. McLaughlin, a citizen of the United States of America, residing at Whiting, in the county of Lake and State of Indiana, have invented a new, original, and ornamental Design for a Match Book Cover, of which the following is a specification, reference being had to the accompanying drawing forming a part thereof.

Fig. 1 is a front elevational view of a match book cover showing my new design;

Fig. 2 is a side elevational view thereof, the dotted lines representing a match book being for illustrative purposes only;

Fig. 3 is a top plan view;

Fig. 4 is a front perspective view; and

Fig. 5 is a rear perspective view.

I claim:

The ornamental design for a match book cover, as shown and described.
